United States Patent Office

Des. 183,485
Patented Sept. 9, 1958

183,485

COAT

Charles Goldstein, Flushing, N. Y.

Application July 2, 1956, Serial No. 42,105

Term of patent 7 years

(Cl. D3—4)

Fig. 1 is a front view of a coat showing my new design;

Fig. 2 is a side view with the sleeves broken away for convenience of illustration;

Fig. 3 is a rear view.

I claim:

The ornamental design for a coat, as shown.
